UNITED STATES PATENT OFFICE.

GEORGE RALPH MORRIS, OF BUFFALO, NEW YORK, ASSIGNOR OF ONE-THIRD TO DAVID Z. MORRIS, OF TORONTO, CANADA.

TELEPHONE-TRANSMITTER.

1,030,915.

Specification of Letters Patent.

Patented July 2, 1912.

Application filed July 22, 1909. Serial No. 508,949.

To all whom it may concern:

Be it known that I, GEORGE RALPH MORRIS, a citizen of the United States, residing at Buffalo, in the county of Erie and State 5 of New York, have invented a new and useful Improvement in Telephone-Transmitters, of which the following is a specification.

This invention relates to improvements in telephone transmitters or microphones 10 which depend for their operation upon variations in electrical resistance due to the action of the vibrating transmitter dia- phragm or other device on a resistance vary- 15 ing device, irrespective of how the vibrations of the diaphragm or device are pro- duced.

The primary object of the invention is to produce a telephone transmitter, or microphone, in which the carbon button or resist- 20 ance varying device is mounted and ar- ranged relative to the diaphragm in a novel manner so as to regulate the action of the telephone and effect a more even reproduc- 25 tion of sounds by augmenting the weaker and softening the stronger sounds.

Other objects of the invention are to mount the carbon button or resistance varying device in a spring or flexible or spring frame which operates as a damper for the 30 diaphragm and acts centrally thereon; also to secure the button-supporting spring or frame in the transmitter casing in such man- ner that it and the diaphragm will be free from strain or stress when the latter is 35 in the normal position; also to arrange the carbon button or resistance varying device so that a change in the position of the 40 transmitter arm will not affect the opera- tion of the transmitter; also to produce a telephone transmitter which is of simple and inexpensive construction and can be quickly and easily repaired; and also to improve the microphone or telephone transmitters in the respects hereinafter described and set forth 45 in the claims.

In the accompanying drawings: Figure 1 is a longitudinal sectional elevation of a telephone transmitter embodying the invention. Fig. 2 is a sectional elevation thereof 50 in line 2-2, Fig. 1. Fig. 3 is a fragmentary sectional elevation, on an enlarged scale, similar to Fig. 1. Fig. 4 is a sectional plan view thereof in line 4-4, Fig. 1.

Like reference characters refer to like 55 parts in the several figures.

A represents the casing, B the arm or support therefor, C the diaphragm, and D the carbon button or resistance varying device of a telephone transmitter or microphone. The casing may be of any usual or suitable 60 form and construction, that shown in the drawings having a removable screw cap or end a provided with a mouth-piece a', and being secured on the arm B in the usual way. The diaphragm is preferably clamped at its 65 edge between the body and removable cap of the casing.

The carbon button or resistance varying device D may be of ordinary construction, consisting of electrodes d d' connected to 70 but insulated from a receptacle d'' in which the carbon granules are confined between the electrodes, but the button is mounted and arranged relative to the diaphragm in the following novel manner: E represents 75 a spring or flexible metal, or spring frame which is secured centrally to the diaphragm by a screw e, or other means, and extends inwardly from the diaphragm, being rigidly secured at its inner side in the casing in the manner hereinafter explained, so as to prevent strain or stress on the diaphragm when the latter is in its normal position. The button is arranged within this spring or frame is rigidly held at its inner side the 80 cured to the opposite sides of the frame, whereby the button is supported with its axis at right angles to the axis of the dia- phragm or so that the electrodes move in a direction substantially parallel with the 85 plane of the diaphragm, instead of at right angles thereto, as in the usual arrangement. f f' represent the telephone conductors which are connected in any suitable way to the electrodes d and d''. The spring or 90 frame may be of the polygonal shape shown in the drawings, or of circular, elliptical or other suitable form. As the spring or frame is rigidly held at its inner side the 95 vibrations of the diaphragm or device al- ternately elongate and shorten the spring in the direction of the axis of the button, so that the inward movements of the dia- phragm spread the electrodes d, d' apart, or 100 decrease the pressure thereof on the carbon granules of the button and increase the elec- trical resistance between the electrodes, whereas the return movements of the dia- phragm press the electrodes toward each 105 other and decrease the electrical resistance, 110

which results in materially augmenting the weak sounds and modulating the loud sounds transmitted by the diaphragm, thus producing a regulating effect upon, or a 5 more even reproduction of the sounds.

By mounting the carbon button in the spring frame in the manner described, the movement of the electrodes may be made equal to, greater than, or less than the corresponding movement of the diaphragm, depending upon whether the length of the 10 spring frame along the axis of the diaphragm is equal to, longer, or less than the width of the frame along the axis of the 15 button. By making the movement of the electrodes greater than that of the button, the sound at the receiver can be magnified. This arrangement of the button permits the 20 same to be located in the plane in which the transmitter diaphragm swings, and a change in the position of the arm will therefore not disturb the carbon granules or cause 25 arcing and affect the action of the transmitter.

The spring frame E being attached to the diaphragm also acts as a damper spring for regulating the vibrations of the diaphragm, and this spring can be supplemented, if necessary, by another spring G of similar character which is arranged, as shown, at right angles to the button-supporting and damper spring E. This dampening action can be regulated as required to suit different conditions, by using one or more springs, or 30 springs of different stiffness or shape. As the damper springs act on the center of the diaphragm they produce a uniform and concentric effect upon its vibrations and give 35 much better results than damper springs which bear on the peripheral portion of the diaphragm.

The button-supporting and dampening springs are preferably secured in the casing as follows: The springs are secured to a bolt 45 or post H which passes loosely through a hole in a disk h, secured by screws h', or otherwise, in the inner end of the casing, and is provided with a head, nut or enlargement h². After the diaphragm with the 50 springs attached thereto has been secured in place in the casing with the bolt extending through the hole in the disk h, the space in the inner end of the casing around the enlargement of the bolt is filled with plaster

of Paris, or other suitable plastic material, 55 which hardens and fastens the bolt rigidly in the position which it naturally assumes, so that the springs and diaphragm will be free from all stress or strain when the diaphragm is in the normal position.

The described construction enables the transmitter to be readily repaired. The diaphragm can be detached and removed by unscrewing the screw which fastens it to the button-supporting spring and the button 60 can then be easily removed from the spring and replaced by a new button. If necessary to remove the button and its springs from the casing, this can be easily done by loosening the disk h and forcing the same and the 65 plastic plug inwardly into the casing.

I claim as my invention:

1. In an electric telephone transmitter, the combination with a vibratory diaphragm, of a resistance varying device, 75 means connecting said resistance varying device to said diaphragm and to a fastening post, and a body of plastic material in which said post is embedded and rigidly held, whereby said post can be placed in the 80 plastic material in such a position that there will be no stress on the diaphragm when the plastic material hardens and secures the post, substantially as set forth.

2. In an electric telephone transmitter, 85 the combination with the vibratory diaphragm, of a resistance varying device having electrodes which are movable in a direction at right angles to the axis of the diaphragm, a spring which surrounds the resistance varying device and is connected at 90 opposite sides to said electrodes, said spring being attached at one side to the diaphragm and at the opposite side to a fastening post, 95 and a body of plastic material in which said post is embedded and rigidly held, whereby said post can be placed in the plastic material in such position that there will be no stress on the diaphragm when the plastic material hardens and secures the post, substantially as set forth.

Witness my hand, this 16th day of July, 100
1909.

GEORGE RALPH MORRIS.

Correction in Letters Patent No. 1,030,915.

It is hereby certified that in Letters Patent No. 1,030,915, granted July 2, 1912, upon the application of George Ralph Morris, of Buffalo, New York, for an improvement in "Telephone-Transmitters," an error appears in the printed specification requiring correction as follows: Page 1, line 85, strike out the words "is rigidly held at its inner side the" and insert the words, reference letters, and syllable *with its opposite electrodes d a' ee-*; and that the said Letters Patent should be read with this correction therein that the same may conform to the record of the case in the Patent Office.

Signed and sealed this 23rd day of July, A. D., 1912.

[SEAL.]

C. C. BILLINGS,
Acting Commissioner of Patents.
